INTEGRATED JET PUMP STRUCTURE

William J. Ekey, Ashland, Ohio, assignor to The F. E. Myers & Bro. Co., Ashland, Ohio, a corporation of Ohio

Filed Jan. 17, 1962, Ser. No. 168,013
9 Claims. (Cl. 103—37)

This invention relates to centrifugal pumps and, more particularly still, to a centrifugal pump and drive motor combination forming an integral unit.

The primary object of the present invention is the provision of a centrifugal pump which is jet assisted which can readily be converted from shallow well to deep well operation.

Another object of this invention is the provision of the combination of a centrifugal pump and a drive motor therefor which is integrated into a single unit thereby resulting in an extremely compact construction.

Still another object of this invention is the provision of a centrifugal pump and motor combination in which various parts are integrally combined with other parts thereby resulting in a minimum number of castings.

Still another object of this invention is the provision of a centrifugal pump arrangement in which the water pumped by the pump cools the bearings of the pump and also cools the seal area to provide for good operating conditions of the pump.

A still further object of this invention is the provision of a centrifugal pump with a take-off for supplying fluid to an assisting jet pump in which the fluid take-off is so arranged that substantially air free water is delivered to the ejector of the jet pump.

These and other objects and advantages of this invention will become more apparent upon reference to the following specification, taken in connection with the accompanying drawings, in which:

FIGURE 1 is a perspective view showing a pump according to the present invention arranged for deep well operation;

FIGURE 2 is a longitudinal vertical sectional view indicated by line 2—2 on FIGURE 1;

FIGURE 3 is a transverse sectional view indicated by line 3—3 on FIGURE 2;

FIGURE 4 is a vertical sectional view indicated by line 4—4 on FIGURE 1;

FIGURE 5 is a fragmentary perspective view showing how the diffuser of the pump is formed integrally with the pump cover plate;

FIGURE 6 is a perspective view of a modified arrangement of a pump according to the present invention;

FIGURE 7 is a longitudinal section through the pump of FIGURE 6 as indicated by line 7—7 on FIGURE 6;

FIGURE 8 is a fragmentary view showing one manner of constructing a panel mounted on the motor and which carries the control devices for controlling the operation of the pump; and

FIGURE 9 is a view like FIGURE 8 but shows a different arrangement of the said panel.

Referring to the drawings somewhat more in detail, in FIGURE 1 there is shown a receiver tank 10 adapted for being supplied by a centrifugal pump 12 that is driven by an electric motor 14. Pump 12 has an inlet conduit 16 leading thereto and a conduit 18 leading therefrom for supplying water under pressure to the jet of a jet pump. The jet pump is indicated generally at 20 and the conduits 16 and 18 are connected to one side thereof while a suction conduit 22 leads from the other side thereof into a well.

Referring now to FIGURE 2, the pump 12 comprises a main casting 24 that is provided with an outer chamber portion 26 having a threaded hole at the top for receiving conduit means 28 that connects the pump with receiver

2

tank 10. Casting 24 at the back has a cylindrical portion 30 extending therefrom which serves as the casing for the electric drive motor 14. The cylindrical portion 30 has a shouldered cylindrical bore 32 therein into which is pressed the stator frame 34 of the electric motor.

The electric motor also comprises a rotor 36 which rotor is pressed on a shaft 38 that has no bearing at its left end. Instead, the shaft 38 is supported in sealed bearings 40 which are fitted into a hub 42 which also forms an integral part of casting 24. The hub 42 is formed in the back wall 44 of chamber 26 and which wall also forms one end wall of the electric motor compartment.

The outer end of the motor is enclosed by a sheet metal cover 46 which telescopically engages the outer end of portion 30 of the main casting of the pump. This portion of the pump may comprise recess means 48 and the sheet metal cover may include indentations 50 so that the cover can be snapped in place on the main pump casting and retained thereon. A screened air inlet opening 52 is provided for the circulation of air through the motor by means of fan 54 carried by the rotor. The air so drawn into the motor passes therethrough and then emerges through the slots 56 formed about the bottom part of the cylindrical portion 30 of the pump casting.

The control wires 58 for the motor lead through the top of the motor housing and into a casing 60 in which there may be mounted a pressure switch.

Located inside chamber 26 and attached to the aforementioned hub portion 42 is a generally conically formed section 62 that defines a space within which the pump impeller 64 runs. This pump impeller is mounted on the threaded end 66 of shaft 38 for being driven in rotation thereby. Between the impeller and the bearings 40 there is preferably provided a fluid seal 68 to prevent or inhibit fluid leakage along shaft 38 from the pump end thereof toward the motor end thereof. Any leakage of fluid getting past seal 68 is prevented from reaching bearings 40 by the provision of a small chamber 70 between the seal and the bearings that is drained by passage 72 leading downwardly therefrom.

According to the present invention, the extreme outer wall of casting 24 is provided with an aperture 74 for receiving an inlet plate or cover plate 76 for the pump. This plate has an inwardly extending cylindrical part 78 that engages an annular planar surface 80 on the adjacent face of the conical section 62 so that the inlet plate or cover plate defines with the conical section a closed chamber in which impeller 64 rotates.

A feature of this invention is illustrated in FIGURES 3 and 5 wherein it will be seen that the inner side plate 78 has integrally formed thereon the arcuate vanes 82 that form the diffuser section through which the fluid pumped by impeller 64 passes from the periphery of the impeller into chamber 26. The forming of the diffuser vanes integrally with the plate 76 eliminates the necessity of the provision of any separate member for the diffuser.

The plate 76 has an outwardly extending boss-like portion 84 having a flat surface 86. On the axis of shaft 36 and extending through portion 84 is a threaded port 88 which receives conduit 16. Located at a lower point and also extending through portion 84 is a threaded port 90 for receiving conduit 18.

The impeller 64 has an axial flange 92 running closely inside bushing 94 mounted in plate 76 and through which axial flange fluid communication is established between the interior of the impeller and the port 88 so that inlet fluid passing through port 88 will move directly into the impeller and be pumped thereby through the diffuser and into chamber 26.

For supplying substantially air free fluid to port 90, there is a port 96 at substantially the lowermost region of vanes 82 that communicates with a chamber 98 leading to

port 90. By this connection, substantially air free water under pressure can be delivered to port 90.

The plate 76 is secured to main casting 24 by bolts distributed about the periphery thereof as will be seen at 100 in FIGURES 1 and 3.

FIGURE 4 shows the inductor assembly when it is arranged for deep well operation. In this view, it will be seen that the jet pump 20 comprises a first body part 102 having an inlet pipe or conduit 22 attached to one side and, at its other side, having a flat surface 106 to which is connected a second body member 108. Second body member 108 has threaded ports for receiving conduit 18 that communicates through the body parts with a jet 110.

Body part 108 threadedly receives conduit 16. Conduit 16 communicates with a chamber 112 that is connected with chamber 114 of body part 102 that leads to conduit 22.

Chamber 114 also communicates with the inlet end of a venturi tube 116 attached to body part 102 and extending into conduit 16. Nozzle 110 directs its jet into the throat of venturi tube 116.

The arrangement is such that body part 102, which is secured to body part 108 by bolts 118, can be detached from body part 108, and, instead, mounted on the flat face 86 of portion 84 of the main pump casting. With body part 102 mounted in this manner, port 90 will communicate with the chamber leading to the nozzle while chamber 114 of body part 102 will communicate with port 88. A venturi tube of a suitable design threaded into the threaded opening 120 of impeller 64 will then be positioned to receive the jet from the nozzle and this will convert the pumping assembly to shallow well operation.

FIGURES 7 through 9 show a somewhat modified arrangement wherein the main casting is indicated at 200. This main casting has a rearwardly projecting generally cylindrical portion 202 in which is mounted stator 204 of an electric drive motor that has a rotor 206 fixed to shaft 208. Shaft 208 extends through bearing means 210 carried in a hub 212 of the main body casting, said shaft extending completely through the bearing and carrying the pump impeller 214 disposed at the face of the conical portion 216 of the main casting. The cover plate means 218 that confines the impeller is the same as that disclosed and described in connection with the first modification.

In FIGURE 7, however, the hub 212 is spaced from the wall portion 220 at the smaller end of the conical portion 216 and in wall portion 220 is the seal 222. The hub 212, on the other hand, is located in another wall portion 224 that is spaced from wall 220 so that there is defined between the said walls passage means 224 through which cooling air can circulate as indicated by arrow 225.

As in the case of the first modification, there is a sheet metal cover 228 enclosing the outer end of the motor with this covering including an air inlet opening screened by a screen 230.

In the FIGURES 7 through 9 modification, the main casting of the motor comprises a flat side wall 232 adapted for detachably supporting a panel 234 which is illustrated in FIGURE 8. A cover member 236 (FIGURE 6) is adapted for detachably mounting on plate 234. Plate 234 carries the operating auxiliaries for the motor of the pump, such as the pressure switch and relay and, if the motor is a condenser start motor, the said condenser.

In the FIGURE 8 modification, all of these auxiliaries are mounted on the outer side of the panel whereas, in FIGURE 9, which shows a similar panel 236, at least one of the auxiliaries 238 is mounted on the back of the panel and is thus disposed in a cavity in the main casting. Panel 236 has a pressure switch 240 mounted on the outer face thereof.

From the foregoing, it will be seen that the present invention provides for an extremely compact and low cost pump which consists of a relatively few and easily ma-

chinable parts readily convertible from deep well to shallow well operation and vice versa. Substantially air free water is provided in either case for the inductor assembly.

It will be understood that this invention is susceptible to modifications and in order to adapt it to different usages and conditions and, accordingly, it is desired to comprehend such modifications within this invention as may fall within the scope of the appended claims.

I claim:

- 10 1. In a centrifugal pump, a main body part having a hub, an impeller shaft journaled in said hub, an impeller on said shaft, an inner body portion extending from one side of the hub to enclose the back of the impeller, an outer body portion extending from the hub outwardly in spaced surrounding relation to said inner body portion and defining with said inner portion a chamber for receiving liquid pumped by the impeller, an inlet plate fixed to said outer body portion to close said chamber and having a portion engaging said inner body portion and confining the periphery of the impeller of the pump, diffuser means formed on the impeller side of the inlet plate about the periphery of the impeller for conducting fluid from the periphery of the impeller to said chamber, a cylindrical projection integral with 15 said outer body portion and on the side of said outer body portion opposite said inlet plate, and an electric motor stator in said projection.

20 2. In a centrifugal pump; a unitary main body part having a hub for rotatably receiving a drive shaft, a drive shaft rotatable in the hub having a pump impeller on one end and a motor rotor on the other end, an inner body portion extending from the hub to a position adjacent the periphery of the impeller, an outer body portion extending from the hub outwardly in surrounding spaced 25 relation to said inner body portion, said body portions defining therebetween a chamber for receiving liquid pumped by said impeller, said body portions having parallel flat rims at their ends opposite said hub, an inlet plate engaging said rims to close said chamber and to 30 confine the pump impeller, diffuser means formed integrally with said plate around the periphery of the impeller to conduct fluid from the impeller to said chamber, a cavity in said plate adjacent the bottom of the chamber, port means in the plate connecting the cavity with 35 the chamber to receive substantially air-free water under pressure from the chamber, a cylindrical projection coaxial with and integral with said hub extending in a direction from the hub opposite said body portions, and a 40 stator for said rotor in said projection.

45 3. In a centrifugal pump; a unitary main body part having a hub, bearings in said hub, a drive shaft supported by said bearings having a motor rotor on one end and a pump impeller on the other end, an inner body portion integral with the hub extending axially and outwardly therefrom to adjacent the periphery of the impeller to form a conical shroud for the back of the impeller, an outer body portion integral with and extending from the hub outwardly and then axially in spaced surrounding 50 relation to said first body portion to define a chamber to receive liquid pumped by the impeller, said body portions terminating at their ends opposite the hub in rim portions which are parallel to each other and perpendicular to the axis of the hub, an inlet plate engaging said rims to close said chamber and to confine the pump 55 impeller, diffuser means integrally formed on the plate extending about the periphery of the impeller to conduct fluid pumped thereby to said chamber, an inlet port in said plate communicating with the eye of the impeller, a cavity on said plate for supplying fluid to the nozzle of a jet pump, a channel leading from said cavity to the bottom of said chamber for supplying substantially air-free liquid to said cavity, a cylindrical projection integral with said body part and projecting therefrom on the side of the hub opposite the impeller coaxial with the 60 hub, and a stator for said rotor and said projection.

65 70 75

4. In a centrifugal pump; a pump casing having a hub, a shaft extending through the hub having a motor rotor on one end on one side of the hub and a pump impeller on the other end on the other side of the hub, bearings on the shaft in the hub forming the sole support of the shaft, a conical casing part integral with the hub and extending therefrom to adjacent the periphery of the impeller, an outer casing part integral with the hub and extending outwardly and then toward the impeller so as to be in spaced surrounding relation to said conical casing part, said parts terminating in rims parallel to each other and perpendicular to said shaft, an inlet plate engaging said rims and closing the chamber between said parts and also enclosing said impeller, a diffuser integrally formed in said plate around the periphery of the impeller to conduct liquid pumped by the impeller to said chamber, an inlet passage in said plate leading to the inlet of the impeller, a cavity in said plate, passage means leading from said cavity to the bottom of said chamber for the supply of substantially air-free liquid under pressure to said cavity, said casing including a cylindrical part integral with and coaxial with said hub extending from the side of the casing opposite said inlet plate, a stator supportingly engaged by said cylindrical part and surrounding said rotor, and a cover member enclosing the outer end of the stator and rotor.

5. In a centrifugal pump; a pump casing having a hub, a shaft extending through the hub having a motor rotor on one end on one side of the hub and a pump impeller on the other end on the other side of the hub, bearings on the shaft in the hub forming the sole support of the shaft, a seal in said hub between said bearings and said impeller, and a drain passage leading from the hub between said seal and said bearings, a conical casing part integral with the hub and extending therefrom to adjacent the periphery of the impeller, an outer casing part integral with the hub and extending outwardly and then toward the impeller so as to be in spaced surrounding relation to said conical casing part, said parts terminating in rims parallel to each other and perpendicular to said shaft, an inlet plate engaging said rims and closing the chamber between said parts and also enclosing said impeller, a diffuser integrally formed in said plate around the periphery of the impeller to conduct liquid pumped by the impeller to said chamber, an inlet passage in said plate leading to the inlet of the impeller, a cavity in said plate, passage means leading from said cavity to the bottom of said chamber for the supply of substantially air-free liquid under pressure to said cavity, said casing including a cylindrical part integral with and coaxial with said hub extending from the side of the casing opposite said inlet plate, a stator supportingly engaged by said cylindrical part and surrounding said rotor, and a cover member enclosing the outer end of the stator and rotor.

6. In a centrifugal pump; a pump casing having a hub, a shaft extending through the hub having a motor rotor on one end on one side of the hub and a pump impeller on the other end on the other side of the hub, bearings on the shaft in the hub forming the sole support of the shaft, a conical casing part integral with the hub and extending therefrom to adjacent the periphery of the impeller, an outer casing part integral with the hub and extending outwardly and then toward the impeller so as to be in spaced surrounding relation to said conical casing part, said parts terminating in rims parallel to each other and perpendicular to said shaft, an inlet plate engaging said rims and closing the chamber between said parts and also enclosing said impeller, a diffuser integrally formed in said plate around the periphery of the impeller to conduct liquid pumped by the impeller to said chamber, an inlet passage in said plate leading to the inlet of the impeller, a cavity in said plate, passage means leading from said cavity to the bottom of said chamber for the supply of substantially air-free liquid under pressure to said cavity, said casing including a

cylindrical part integral with and coaxial with said hub extending from the side of the casing opposite said inlet plate, a stator supportingly engaged by said cylindrical part and surrounding said rotor, and a cover member enclosing the outer end of the stator and rotor, a substantial portion of the length of said hub being located in said chamber so as to be in direct heat transfer relation with the liquid therein.

7. A casing for a centrifugal pump, said casing comprising a unitary casting having a central cylindrical hub portion, bearings in said hub portion at one end and a seal in said hub portion at the other end, a pump drive shaft in the hub portion supported by said bearings and sealed therein by said seal, a pump impeller on said shaft, said casing comprising a first portion extending outwardly from the said other end of the hub for enclosing the back of the pump impeller, said casing comprising a second portion extending from the hub adjacent the said one end thereof, said second portion extending generally radially outwardly and then toward the said other end of the hub so as to be in surrounding relation with the said first portion whereby to define a space for receiving liquid pumped by the pump impeller and which liquid surrounds a substantial portion of the length of said hub so as to be in direct heat transfer relation therewith, a generally cylindrical projection extending from the back of said second portion coaxial with said hub, an electric drive motor stator supported in said projection, a rotor in the stator connected to said shaft, said second portion having a central aperture therein on the end remote from the hub coaxial with the hub, and an inlet plate mounted in said aperture closing the said aperture and including an integral diffuser portion engaging the outer end of said first portion and confining therewith a space for the impeller of the pump.

8. A casing for a centrifugal pump, said casing comprising a unitary casting having a central cylindrical hub portion, bearings in said hub portion at one end and a seal in said pump portion at the other end, a pump drive shaft in the hub portion supported by said bearings and sealed therein by said seal, a pump impeller on said shaft, said casing comprising a first portion extending outwardly from the said other end of the hub for enclosing the back of the pump impeller, said casing comprising a second portion extending from the hub adjacent the said one end thereof, said second portion extending generally radially outwardly and then toward the said other end of the hub so as to be in surrounding relation with the said first portion whereby to define a space for receiving liquid pumped by the pump impeller and which liquid surrounds a substantial portion of the length of said hub so as to be in direct heat transfer relation therewith, a generally cylindrical projection extending from the back of said second portion coaxial with said hub, an electric drive motor stator supported in said projection, a motor rotor on the shaft and in the stator, said second portion having a central aperture therein on the end remote from the hub coaxial with the hub, and an inlet plate mounted in said aperture closing the said aperture and including an integral diffuser portion engaging the outer end of said first portion and confining therewith a space for the impeller of the pump, said inlet plate having an inlet passage therethrough coaxial with said hub communicating with the inlet of an impeller in the pump, and also having a passage for supplying the jet of a jet pump, said last mentioned passage leading through said inlet plate of the said second portion of said casing into the bottom of the space between said first and second portions.

9. In a centrifugal pump; an electric drive motor, a main body part having first means at one end to support said electric drive motor and second means at the other end defining a pumping chamber, an impeller in said pumping chamber, a drive shaft connecting the motor

with the impeller, first wall means in said main body part comprising a hub rotatably receiving and supporting said shaft, a second wall in said main body part between said first wall and said pumping chamber through which said shaft passes, and seal means carried by said second mentioned wall and surrounding said shaft, said motor comprising air circulating fan means, and passage means extending through said motor and between said walls for the circulation of air through said motor.
